FISH LURE

William R. Haynes, Leicester, N. Y.

Application January 11, 1955, Serial No. 33,921

Term of patent 14 years

(Cl. D31—4)

FIG. 1

Fig. 1 is a front elevational view of the fish lure, showing my design;

Fig. 2 is a side elevational view; and

Fig. 3 is a top plan view thereof.

I claim:

The ornamental design for a fish lure, as shown.
